Britain

Application March 24, 1949, Serial No. 83,153
In Great Britain March 27, 1948

9 Claims. (Cl. 68—58)

1

This invention relates to improvements in machines such as washing machines, dry cleaning machines or garment dyeing machines of the type in which an inner cylinder having its axis horizontal rotates within an outer cylindrical casing.

In such machines the machine is usually filled or partially filled with the liquid employed in the washing, cleaning or dyeing process so that the articles in the inner cylinder are immersed in the liquid, and the object of the present invention is to subject the articles to a flow of liquid through them instead of being merely immersed in the liquid and agitated as the cylinder rotates, and further to draw away the soiled or spent liquid continuously and replace it by fresh liquid.

According to the invention the inner cylinder is imperforate for a portion of its axial length, such imperforate portion carrying perforated lifters provided with scoops for picking up liquid from the annular space between the cylinder and the casing and the remaining portion of the periphery of the cylinder being perforated to allow the escape of the liquid from the cylinder, means being provided for applying liquor to the annular space between the cylinder and the casing and for the removal of the used liquor draining from the cylinder through the perforated portion thereof. In a preferred arrangement the lifters may extend the whole length of the inner cylinder but have the scoops extending only the length of the slots in the casing. In such arrangement both the lifter and the portion of the periphery of the cylinder beyond the slots are perforated for draining of the liquid.

The invention is illustrated in and will be described with reference to the accompanying drawings in which:

Fig. 1 is a longitudinal section through a machine constructed in accordance with the invention;

Fig. 2 is a section on line 2—2 of Fig. 1, and

Fig. 3 is a similar section to Fig. 2 showing a modified construction of inner cylinder.

The inner cylinder A rotates within the outer cylinder casing B being carried at one end on a trunnion b and being provided at the other end with a ring b¹ which is supported on two rollers (not shown). The trunnion b is driven by suitable gearing such as the grooved pulley C shown in the drawing and its direction of rotation is preferably reversed after a predetermined number of revolutions to prevent the goods in the cylinder from becoming tangled.

The cylinder A is provided with a number of perforated lifters D arranged at equal angular

2

distances apart and projecting inwards towards the axis of the cylinder and each lifter is provided with a scoop D¹ on each of its longitudinal edges, the scoops extending for a portion of the length of the cylinder. The lifter D extends for the whole length of the cylinder as shown in Fig. 1 in which case the scoops D¹ only extend for a portion of the lengths of the lifters and at the end of the scoop portion a baffle plate F is fitted and is continued by the annular ring G completely around the periphery of the cylinder so as to fill the annular space between the cylinder and the casing leaving only a running clearance.

The lifter D may be of approximately triangular shape in cross section with the scoops D¹ extending outwardly at a small angle towards each other as shown in Fig. 2. Thus whether the cylinder A is rotating in a clockwise or anti-clockwise direction the scoops D¹ will pick up the liquid from the annular space between the cylinder and casing. Alternatively as shown in Fig. 3 the lifters D may be of truncated triangular shape and each be provided with a separate V-shaped plate d carried by the cylinder end A³ or be otherwise secured so as to rotate with the cylinder, the periphery of the cylinder A at each edge of the lifter being extended and curved inwards to form extensions d¹ which co-operate with the plate d to form an effective scoop which operates in either direction of rotation of the cylinder. The extensions d¹ also act as retainers for the liquid picked up by the lifter.

The part A¹ of the peripheral surface of the cylinder A where there are no scoops D¹ (whether the lifters D extend over this portion or not) is perforated, the remaining part A² of the peripheral surface being unperforated.

Two tanks H and J are arranged in the lower part of the casing B, the tank H corresponding with the unperforated portion A² of the cylinder and the tank J with the perforated portion A¹ thereof.

Communication from tank H to the annular space between the cylinder and casing is by the slots h¹ and h² running axially the full length of the tank. The tank J is open to the annular space without restriction. A feed pipe H¹ is connected to tank H and a rain pipe J¹ to tank J. A weir plate M is arranged close to the ring G.

The casing B is shown with a loading door B¹ at one end but the invention is equally applicable to machines of the side loading type.

The action of the machine is as follows:

Liquid is continuously supplied to the tank H through the pipe H¹ by any suitable means and flows through the slots h¹ and h² into the annular

space below the rotating cylinder A. The scoops D¹ pick up the liquid as the cylinder rotates and the liquid is carried round by the lifters D gradually draining through the perforations therein on to the goods in the cylinder. Part of the liquid picked up will flow immediately through the perforations of the lifters D into the inner cylinder A and part will be carried round by the lifters and pass into the cylinder at higher levels, the size and number of perforations being preferably such that some of the liquid is retained in the lifter until the latter reaches or has passed the highest point in its rotation.

The liquid draining from the goods flows through perforations in the part A¹ of the cylinder and the perforated portion of the lifters opposite thereto into the tank J. The liquid flowing from tank H is prevented from running directly into tank J by the baffle ring G and the weir plate M and the liquid picked up by a lifter is prevented from flowing beyond the end of the scoops of the lifter by the baffle plate F.

Thus as the cylinder rotates the articles therein will be subjected to a continuous flow of the liquid with which they are being washed, cleaned or dyed, and more effective washing, cleaning or dyeing will result than when they are merely immersed in the liquid the dirt being continuously flushed from the machine as it is removed from the goods.

The perforated and imperforate portions of the cylinder A are shown in Fig. 1 as being at its ends, but it will be appreciated that, for instance in a longer cylinder, the imperforate portions may be at the center of its length and perforated portions at each end or vice versa.

Moreover instead of the inlet and outlet to the machine being tanks as shown they may consist of pipes connected directly on to the casing, or to cavities formed on the casing.

I claim:

1. A washing machine comprising, in combination, a stationary substantially cylindrical casing mounted with the axis thereof located in a substantially horizontal position; a substantially cylindrical drum mounted within and concentrically with said casing, the said drum being of a substantially smaller diameter than said casing so as to form an annular space between said drum and said casing, said drum, having a first cylindrical wall portion which is perforated and a second imperforate wall portion forming an extension of said first wall portion, the said second wall portion being formed with a plurality of perforated liquid lifters communicating with said annular space and extending inwardly toward the center of said drum and extending along the length of said second wall portion, the said liquid lifters each being secured along a pair of longitudinal opposite edges thereof to said drum; scoop means connected to said drum and located in the annular space between said casing and said drum for directing liquid in said casing into said liquid lifters; means for rotating said drum; means for permitting the insertion and removal of articles to be washed into and out of said drum; means for continually supplying washing liquid to the space between said second portion of said drum and said casing, so that said liquid may flow into said drum through said perforated liquid lifters and out of said drum through said perforated first portion thereof; and means for continually draining said washing liquid from the space

between said first portion of said drum and said casing.

2. A washing machine comprising, in combination, a stationary substantially cylindrical casing mounted with the axis thereof located in a substantially horizontal position; a substantially cylindrical drum mounted within and concentrically with said casing, the said drum being of a substantially smaller diameter than said casing so as to form an annular space between said drum and said casing, said drum, having a first cylindrical wall portion which is perforated and a second imperforate wall portion forming an extension of said first wall portion, the said second wall portion being formed with a plurality of perforated liquid lifters communicating with said annular space and extending inwardly toward the center of said drum and extending along the length of said second wall portion, the said liquid lifters each being secured along a pair of longitudinal opposite edges thereof to said drum; a plurality of elongated, fixedly mounted scoop members located along said longitudinal edges of said water lifters, overlying a portion of said liquid lifters and extending substantially across the space between said drum and said casing for directing liquid in said casing into said liquid lifters; means for rotating said drum; means for permitting the insertion and removal of articles to be washed into and out of said drum; means for continually supplying washing liquid to the space between said second portion of said drum and said casing, so that said liquid may flow into said drum through said perforated liquid lifters and out of said drum through said perforated first portion thereof; and means for continually draining said washing liquid from the space between said first portion of said drum and said casing.

3. A washing machine comprising, in combination, a stationary substantially cylindrical casing mounted with the axis thereof located in a substantially horizontal position; a substantially cylindrical drum mounted within and concentrically with said casing, the said drum being of a substantially smaller diameter than said casing so as to form an annular space between said drum and said casing, said drum, having a first cylindrical wall portion which is perforated and a second imperforate wall portion forming an extension of said first wall portion, the said second wall portion being formed with a plurality of perforated liquid lifters communicating with said annular space and extending inwardly toward the center of said drum and extending along the length of said second wall portion, the said liquid lifters each being secured along a pair of longitudinal opposite edges thereof to said drum; a plurality of elongated, fixedly mounted scoop members located along said longitudinal edges of said water lifters, overlying a portion of said liquid lifters and extending substantially across the space between said drum and said casing for directing liquid in said casing into said liquid lifters; an annular baffle member fixed to said drum along the line where said first wall portion joins said second wall portion and extending substantially across the space between said drum and said casing; means for rotating said drum; means for permitting the insertion and removal of articles to be washed into and out of said drum; means for continually supplying washing liquid to the space between said second portion of said drum and said casing, so that said liquid may flow into said drum through said perforated

liquid lifters and out of said drum through said perforated first portion thereof; and means for continually draining said washing liquid from the space between said first portion of said drum and said casing.

4. A washing machine comprising, in combination, a stationary substantially cylindrical casing mounted with the axis thereof located in a substantially horizontal position; a substantially cylindrical drum mounted within and concentrically with said casing, the said drum being of a substantially smaller diameter than said casing so as to form an annular space between said drum and said casing, said drum, having a first cylindrical wall portion which is perforated and a second imperforate wall portion forming an extension of said first wall portion, the said second wall portion being formed with a plurality of perforated liquid lifters communicating with said annular space and extending inwardly toward the center of said drum and extending along the length of said second wall portion, the said liquid lifters each being secured along a pair of longitudinal opposite edges thereof to said drum; a plurality of elongated, fixedly mounted scoop members located along said longitudinal edges of said water lifters, overlying a portion of said liquid lifters and extending substantially across the space between said drum and said casing for directing liquid in said casing into said liquid lifters; an annular baffle member fixed to said drum along the line where said first wall portion joins said second wall portion and extending substantially across the space between said drum and said casing; means for rotating said drum; means for permitting the insertion and removal of articles to be washed into and out of said drum; means for continually supplying washing liquid to the space between said second portion of said drum and said casing, said last-mentioned means comprising a first tank mounted beneath said casing at the portion thereof which overlies said second portion of said drum and a supply pipe for supplying washing liquid to said first tank, said casing being formed with openings passing therethrough and communicating with said first tank whereby the liquid in said first tank may flow to the space between said casing and said second portion of said drum and so that said liquid may flow into said drum through said perforated liquid lifters and out of said drum through said perforated first portion and thereof; and means for continually draining said washing liquid from the space between said first portion of said drum and said casing, said last-mentioned means comprising a second tank located adjacent to said first tank and mounted beneath that portion of said casing which overlies said first portion of said drum, said casing being formed with an opening therein which communicates with said second tank so as to permit the water in said space between said casing and said first portion of said drum to flow into said second tank, and a drain pipe connected to said second tank for drawing off the water therefrom.

5. A washing machine comprising, in combination, a stationary substantially cylindrical casing mounted with the axis thereof located in a substantially horizontal position; a substantially cylindrical drum mounted within and concentrically with said casing, the said drum being of a substantially smaller diameter than said casing so as to form an annular space between said drum and said casing, said drum, having a first

cylindrical wall portion which is perforated and a second imperforate wall portion forming an extension of said first wall portion, the said second wall portion being formed with a plurality of perforated liquid lifters communicating with said annular space and extending inwardly toward the center of said drum and extending along the length of said second wall portion, the said liquid lifters each being secured along a pair of longitudinal opposite edges thereof to said drum; a plurality of elongated, fixedly mounted scoop members located along said longitudinal edges of said water lifters, overlying a portion of said liquid lifters and extending substantially across the space between said drum and said casing for directing liquid in said casing into said liquid lifter; an annular baffle member fixed to said drum along the line where said first wall portion joins said second wall portion and extending substantially across the space between said drum and said casing; means for rotating said drum; means for permitting the insertion and removal of articles to be washed into and out of said drum; means for continually supplying washing liquid to the space between said second portion of said drum and said casing, said last-mentioned means comprising a first tank mounted beneath said casing at the portion thereof which overlies said second portion of said drum and a supply pipe for supplying washing liquid to said first tank, said casing being formed with openings passing therethrough and communicating with said first tank whereby the liquid in said first tank may flow to the space between said casing and said second portion of said drum and so that said liquid may flow into said drum through said perforated liquid lifters and out of said drum through said perforated first portion thereof; means for continually draining said washing liquid from the space between said first portion of said drum and said casing, said last-mentioned means comprising a second tank spaced from said first tank and mounted beneath that portion of said casing which overlies said first portion of said drum, said casing being formed with an opening therein which communicates with said second tank so as to permit the water in said space between said casing and said first portion of said drum to flow into said second tank, and a drain pipe connected to said second tank for drawing off the water therefrom; and weir means mounted in said casing along and upward of a wall of said second tank for deterring the flow of said washing liquid directly from said first tank into said second tank.

6. A washing machine comprising, in combination, a stationary substantially cylindrical casing mounted with the axis thereof located in a substantially horizontal position; a substantially cylindrical drum mounted within and concentrically with said casing, the said drum being of a substantially smaller diameter than said casing so as to form an annular space between said drum and said casing, said drum, having a first cylindrical wall portion which is perforated and a second imperforate wall portion forming an extension of said first wall portion, the said second wall portion being formed with a plurality of perforated liquid lifters communicating with said annular space and extending inwardly toward the center of said drum and extending along the length of said second wall portion, the said liquid lifters each being secured along a pair of longitudinal opposite edges thereof to said

drum; a plurality of scoop members fixedly connected to said longitudinal edges of said water lifters and overlying a portion of said liquid lifters, the said scoop members being curved inwardly toward the center of said drum; a plurality of vane members connected to said drum so as to rotate therewith and located adjacent to but slightly spaced from said scoop members so as to form therewith a means for directing liquid from the space between said drum and said casing into said liquid lifters; means for rotating said drum; means for permitting the insertion and removal of articles to be washed into and out of said drum; means for continually supplying washing liquid to the space between said second portion of said drum and said casing, so that said liquid may flow into said drum through said perforated liquid lifters and out of said drum through said perforated first portion thereof; and means for continually draining said washing liquid from the space between said first portion of said drum and said casing.

7. A washing machine comprising, in combination, a stationary substantially cylindrical casing mounted with the axis thereof located in a substantially horizontal position; a substantially cylindrical drum mounted within and concentrically with said casing, the said drum being of a substantially smaller diameter than said casing so as to form an annular space between said drum and said casing, said drum, having a first cylindrical wall portion which is perforated and a second imperforate wall portion forming an extension of said first wall portion, the said second wall portion being formed with a plurality of perforated liquid lifters communicating with said annular space and extending inwardly toward the center of said drum and extending along the length of said second wall portion, the said liquid lifters each being secured along a pair of longitudinal opposite edges thereof to said drum; a plurality of scoop members fixedly connected to said longitudinal edges of said water lifters and overlying a portion of said liquid lifters, the said scoop members being curved inwardly toward the center of said drum; a plurality of vane members connected to said drum so as to rotate therewith and located adjacent to but slightly spaced from said scoop members so as to form therewith a means for directing liquid from the space between said drum and said casing into said liquid lifters; an annular baffle member fixed to said drum along the line where said first wall portion joins said second wall portion and extending substantially across the space between said drum and said casing; means for rotating said drum; means for permitting the insertion and removal of articles to be washed into and out of said drum; means for continually supplying washing liquid to the space between said second portion of said drum and said casing, said last-mentioned means comprising a first tank mounted beneath said casing at the portion thereof which overlies said second portion of said drum and a supply pipe for supplying washing liquid to said first tank, said casing being formed with openings passing therethrough and communicating with said first tank whereby the liquid in said first tank may flow to the space between said casing and said second portion of said drum and so that said liquid may flow into said drum through said perforated liquid lifters and out of said drum through said perforated first portion thereof; and means for continually draining said washing liquid from the space between said first portion of said drum and said casing, said last-mentioned means comprising a second tank located adjacent to said first tank and mounted beneath that portion of said casing which overlies said first portion of said drum, said casing being formed with an opening therein which communicates with said second tank so as to permit the water in said space between said casing and said first portion of said drum to flow into said second tank, and a drain pipe connected to said second tank for drawing off the water therefrom.

8. A washing machine comprising, in combination, a stationary substantially cylindrical casing mounted with the axis thereof located in a substantially horizontal position; a substantially cylindrical drum mounted within and concentrically with said casing, the said drum being of a substantially smaller diameter than said casing

so as to form an annular space between said drum and said casing, said drum, having a first cylindrical wall portion which is perforated and a second imperforate wall portion forming an extension of said first wall portion, the said second wall portion being formed with a plurality of perforated liquid lifters communicating with said annular space and extending inwardly toward the center of said drum and extending along the length of said second wall portion, the said liquid lifters each being secured along a pair of longitudinal opposite edges thereof to said drum; a plurality of scoop members fixedly connected to said longitudinal edges of said water lifters and overlying a portion of said liquid lifters, the said scoop members being curved inwardly toward the center of said drum; a plurality of vane members connected to said drum so as to rotate therewith and located adjacent to but slightly spaced from said scoop members so as to form therewith a means for directing liquid from the space between said drum and said casing into said liquid lifters; an annular baffle member fixed to said drum along the line where said first wall portion joins said second wall portion and extending substantially across the space between said drum and said casing; means for rotating said drum; means for permitting the insertion and removal of articles to be washed into and out of said drum; means for continually supplying washing liquid to the space between said second portion of said drum and said casing, said last-mentioned means comprising a first tank mounted beneath said casing at the portion thereof which overlies said second portion of said drum and a supply pipe for supplying washing liquid to said first tank, said casing being formed with openings passing therethrough and communicating with said first tank whereby the liquid in said first tank may flow to the space between said casing and said second portion of said drum and so that said liquid may flow into said drum through said perforated liquid lifters and out of said drum through said perforated first portion thereof; and means for continually draining said washing liquid from the space between said first portion of said drum and said casing, said last-mentioned means comprising a second tank located adjacent to said first tank and mounted beneath that portion of said casing which overlies said first portion of said drum, said casing being formed with an opening therein which communicates with said second tank so as to permit the water in said space between said casing and said first portion of said drum to flow into said second tank, and a drain pipe connected to said second tank for drawing off the water therefrom.

9. A washing machine comprising, in combination, a stationary substantially cylindrical casing mounted with the axis thereof located in a substantially horizontal position; a substantially cylindrical drum mounted within and concentrically with said casing, the said drum being of a substantially smaller diameter than said casing so as to form an annular space between said drum and said casing, said drum, having a first cylindrical wall portion which is perforated and a second imperforate wall portion forming an extension of said first wall portion, the said second wall portion being formed with a plurality of perforated liquid lifters communicating with said annular space and extending inwardly toward the center of said drum and ex-

tending along the length of said second wall portion, the said liquid lifters each being secured along a pair of longitudinal opposite edges thereof to said drum; a plurality of scoop members fixedly connected to said longitudinal edges of said water lifters and overlying a portion of said liquid lifters, the said scoop members being curved inwardly toward the center of said drum; a plurality of vane members connected to said drum so as to rotate therewith and located adjacent to but slightly spaced from said scoop members so as to form therewith a means for directing fluid from the space between said drum and casing into said liquid lifters; an annular baffle member fixed to said drum along the line where said first wall portion joins said second wall portion and extending substantially across the space between said drum and said casing; means for rotating said drum; means for permitting the insertion and removal of articles to be washed into and out of said drum; means for continually supplying washing liquid to the space between said second portion of said drum and said casing, said last-mentioned means comprising a first tank mounted beneath said casing at the portion thereof which overlies said second portion of said drum and a supply pipe for supplying washing liquid to said first tank, said casing being formed with openings passing therethrough and communicating with said first tank whereby the liquid in said first tank may flow to the space between said casing and said second portion of said drum and so that said liquid may flow into said drum through said perforated liquid lifters and out of said drum

20
